DISPLAY RACK

Leo F. McLennan, Chicago, Ill.

Application September 14, 1955, Serial No. 534,191

3 Claims. (Cl. 312—45)

This invention relates generally to a display rack construction. The instant display rack has been particularly constructed for use with a composite base carrying a card rack and having display shelving between the base and card rack.

Today retailers all over the country are engaging in the highly profitable business of selling greeting cards. The racks presently used to display these cards require a very considerable amount of expensive store space.

Many retailers also are engaged in selling gift wrapping materials. These gift wrapping materials are also space consuming and heretofore have required separate display accommodations.

The present invention concerns itself with the provision of an intermediate display shelving sandwiched between the base and card rack now most commonly employed to the end of greatly reducing the overall space required for displaying the aforementioned merchandise and in so doing, utilizing space formerly completely wasted.

From a merchandiser's standpoint the instant display rack construction is highly advantageous since it greatly promotes tie-in sales of greeting cards and gift wrapping materials.

Accordingly it is an object of this invention to provide a highly simple display rack construction for displaying 40 both greeting cards and gift wrapping materials.

Still another object of this invention is to provide a display rack construction which is relatively inexpensive to manufacture, and which greatly reduces the amount of floor space presently used to display the same merchandise.

A further object of this invention is to provide a display rack construction which greatly promotes tie-in sales of merchandise.

According to the general features of this invention there is provided in a composite display structure including a base and a display rack carried thereon, intermediate display shelving sandwiched between the base and rack including a relatively narrow shelf supported over the base forwardly of the rack and an upwardly and rearwardly inclined support for rolls of merchandise extending under the rack having an outer forward edge below and spaced from the rear edge of the shelf to a distance less than the diameter of the merchandise rolls so that the rolls can gravitate downwardly on said support into an exposed position of rest on the spaced edges of the shelf and support outwardly of the rack but over the forward portion of the base.

Another feature of this invention relates to the provision of an intermediately located inclined feeder shelf having adjustable dividers for accommodating various widths of rolls of merchandise.

Other objects and features of this invention will more fully appear from the following detailed description taken in connection with the accompanying drawings which illustrate a single embodiment thereof and in which:

2

Figure 1 is a front elevation of my novel display rack embodying features of this invention;

Figure 2 is a side elevation of the display rack shown in Figure 1;

5 Figure 3 is a fragmentary enlarged front elevation of the intermediate display shelving embodying features of the present invention;

Figure 4 is a plan view of the intermediate section shown in Figure 3; and

10 Figure 5 is an enlarged longitudinal section showing the detail of a notched strip for accommodating stock spacing wires.

As shown on the drawings:

The reference numeral 10 indicates generally my novel 15 display rack construction which includes a base section 11 having a plurality of drawers 12 positioned below a longitudinally extending rearwardly inclined surface 13 positioned along the upper vertical edge of the section 11. This inclined surface 13 is especially adapted to have 20 suitably mounted thereon indicia 14 for identifying the various merchandise carried upon shelves as will hereinafter become apparent.

Positioned on top of the base section 13 is my novel 25 detachable intermediate section 15 which is most advantageously constructed so as to be capable of having mounted thereon a detachable card rack 16. This card rack 16 may be of the type shown in the J. C. Hall Patent No. 2,067,051 which is especially adapted to highlight and display greeting cards.

30 Any suitable materials may be utilized in building my rack 10 with excellent results being attainable through the use of wood.

My invention is particularly concerned with the construction and operation of the intermediate section 15 35 which is sandwiched between the base 11 and rack 16 in the illustrated embodiment.

The intermediate section 15 includes two side walls 17 and 18 joined together by a rear panel 19. Each of the side walls 17 and 18 has a reduced forward portion (Figs. 1 and 2) defined by a flat edge 20 connected to an arcuate edge 21 leading to a vertically upper edge 22.

40 Insertable within the housing defined by side walls 17 and 18 and rear panel 17 are three identical space dividers and shelf supporters 23. Each of these dividers has a suitable number of slots 24 which are preferably spaced and staggered vertically rearwardly with the lowermost slot extending forwardly of all of the vertically upper slots; the same being true for each of the succeeding slots (Figure 5).

50 Each of the dividers 23 is of a relatively narrow cross section and includes a flat bottom 25 (Fig. 5) which is adapted to rest upon cabinet top 26; and a relatively flat rear wall 27 which is adapted to bottom against rear panel 19 (Fig. 5).

55 The dividers 23 have a vertically upwardly offset edge 28 coplanar with edges 20 which are adapted to provide a rest for a transparent member or shelf 29 which may be constructed of a suitable material such as glass or the like.

60 Offset edge 29 is connected to a vertically downwardly angled edge 30 which is in turn connected to a rearwardly upwardly inclined edge or surface 31 adapted to carry an inclined shelf 32 which may be secured to the edges 31 in any suitable manner.

65 Slidably disposed in the slots 24 between the dividers 23 are a series of staggered shelves 33.

In assembly the dividers 23 may be assembled with upwardly staggered shelves or racks 33 and fastened together by any suitable means such as glue or nails.

70 Thereafter, the divider and shelf assembly may be slid within the housing defined by the side walls 17 and 18

along with rear panel 17 and secured therewith in any suitable manner as previously set forth.

In Figures 3-5 it will be noted that rear panel 19 is notched at 34 along the length of same at predetermined intervals. Similarly, the forward end of shelf 32 has a plurality of longitudinally spaced openings 35 extending a portion of the way through the shelf 32 with each of the openings 35 being in alignment with the rearwardly disposed notch 34. Guide rails or wires 36 each have a hooked end 37 and an extended rearward terminal portion 38 on the opposite end and each may be positioned in the opening 35 and notch 34, respectively in assembly. These guide wires 36 may be placed in any suitable position in order to accommodate variable sized ribbon rolls 39 as is shown in the drawings.

In operation, the guide wires 36 are placed in predetermined longitudinally spaced positions and variable sized rolls may be stacked upon the inclined shelf 32 between the wires 36. Forward edge 40 of shelf 32 is positioned vertically below glass edge 41 and is of a predetermined smaller distance apart than the diameter of the rolls. When a series of rolls 39 are positioned along the inclined plane between the guide wires 36, the lowermost roll is readily viewed by the prospective buyer as it is supported between edges 40 and 41. It is in this manner that the ribbons are constantly in proper position since as one roll of ribbon is removed another will immediately gravitate into position between the previously mentioned edges.

As a prospective card purchaser views the greeting cards carried by the card rack 16, his attention will become diverted to the rolls of ribbon 39 carried slightly to the rear of the glass shelf 29 and to packages of wrapping paper and other like merchandise 42 carried upon cabinet top 26, and shelves 33 respectively, which are all in staggered relation to one another. The prospective purchaser may rest his or her packages and purse upon the glass shelf or counter while viewing through the glass a considerable variety of merchandise 42 (Fig. 3) which may be removed from the forward end of the rack 10 for closer scrutiny and purchase. It will be appreciated the glass shelf additionally serves to keep the merchandise clean.

The merchandise 42 above mentioned may comprise rolls, oval or flat packages of gift dressings of variable lengths, for example, a rolled package of wrapping paper 30" long. This is highly advantageous since the presently known displaying facilities do not accommodate rolls of such length.

The instant rack construction 10 greatly increases the number of tie-in sales since a prospective buyer looking for one type of merchandise such as a greeting card will be reminded that he may also need some other related item such as wrappings and ribbon for a gift.

Another advantage of the instant construction is that formerly wasted space may be utilized to display goods since separate display racks are no longer needed for greeting cards, ribbons and wrappings. Still further the space contained in cavity 43 (Fig. 5) defined by the walls of the card rack may be utilized since the rolls of merchandise may extend therein when resting upon inclined support 32 thereby utilizing formerly wasted space for storing merchandise rolls.

It will be understood that modifications and variations may be effected without departing from the scope of the novel concepts of the present invention, but it is understood that this application is to be limited only by the scope of the appended claims.

I claim as my invention:

1. A roll display and shelving structure including a relatively narrow generally horizontally disposed first shelf for supporting packages and the like having a rear-

ward edge, an upwardly and rearwardly inclined support for rolls of merchandise being disposed generally rearwardly of said shelf, said rearwardly inclined support having an outer forward edge below and spaced from said rearward edge of said shelf to a distance less than the diameter of the merchandise rolls so that the rolls may gravitate downwardly on said support into an exposed position of rest between said rearward edge of the shelf and said outer forward edge, said shelf being transparent, and at least one horizontally disposed second shelf mounted below and staggered forwardly of said outer support edge, said second shelf located below said transparent shelf for carrying merchandise below said transparent shelf and which merchandise may be viewed from above the transparent shelf.

2. A roll display and shelving structure including a relatively narrow generally horizontally disposed first shelf for supporting packages and the like having a rearward edge, an upwardly and rearwardly inclined support for rolls of merchandise being disposed generally rearwardly of said shelf, said rearwardly inclined support having an outer forward edge below and spaced from said rearward edge of said shelf to a distance less than the diameter of the merchandise rolls so that the rolls may gravitate downwardly on said support into an exposed position of rest between said rearward edge of the shelf and said outer forward edge, said shelf being transparent, a second horizontally disposed shelf mounted below and staggered forwardly of said outer support edge, said second shelf located below said transparent shelf for carrying merchandise below said transparent shelf, and a third shelf mounted below said second shelf and staggered forwardly of said second shelf, said second and third shelves adapted to carry merchandise which may be viewed from above said transparent shelf.

3. A roll display and shelving structure including a relatively narrow generally horizontally disposed first shelf for supporting packages and the like having a rearward edge, an upwardly and rearwardly inclined support for rolls of merchandise being disposed generally rearwardly of said shelf, said rearwardly inclined support having an outer forward edge below and spaced from said rearward edge of said shelf to a distance less than the diameter of the merchandise rolls so that the rolls may gravitate downwardly on said support into an exposed position of rest between said rearward edge of the shelf and said outer forward edge, a plurality of guide rails extending rearwardly on said support with a hooked forward end, a plurality of openings in the forward portion of the support and a plurality of notches in the rearward portion of the support for supportingly and adjustably receiving said rails, said first shelf being transparent, and at least one horizontally disposed second shelf mounted below and staggered forwardly of said outer support edge, said second shelf located below said transparent shelf for carrying merchandise below said transparent shelf so that it may be viewed from above the transparent shelf.
